UNITED STATES PATENT OFFICE.

CHARLES E. BERTELS, OF WILKES-BARRE, PENNSYLVANIA.

CAN.

No. 926,461.

Specification of Letters Patent.

Patented June 29, 1909.

Application filed June 20, 1908. Serial No. 439,621.

To all whom it may concern:

Be it known that I, CHARLES E. BERTELS, a citizen of the United States, residing at Wilkes-Barre, in the county of Luzerne and State of Pennsylvania, have invented a new and useful Can, of which the following is a specification.

This invention relates to sheet metal cans or receptacles, and more particularly to that 10 class employing a closure that is held assembled with the receptacle or body by frictional contact with the rim or mouth portion thereof.

The object of the present invention is to 15 improve the manner of assembling the closure or cap with the rim or mouth of the receptacle, whereby to secure an absolutely air tight joint, and at the same time not to increase the resistance to removal of the 20 closure.

It may be stated at this point that it is 25 recognized to be old to provide the mouth of a can or receptacle with a jointless rim with which a cupped portion of the closure interlocks to hold the latter in position. Rims of this character generally employed have 30 that face which contacts with the cupped portion of the closure flat, so that unless there be an absolute contact between all portions of the rim and of the cupped closure an air tight joint cannot be secured.

That which differentiates the present invention from the rim above defined is that 35 the seal of the rim, or that part with which the cupped portion of the closure contacts is approximately circular in cross section, so that only a minute portion of the exterior of the seal will contact with the closure, whereby a tighter fitting union can be secured 40 with less resistance to assemblage and disconnection of the parts. A further feature of difference is that the seal portion of the rim has its upper edge disposed flush or substantially so with the like portion of the rim 45 proper, thus to facilitate the removal of all of the contents of the can or receptacle.

With the above and other objects in view, 50 as will appear as the nature of the invention is better understood the same consists in the various novel details of construction of a can closure, as will be hereinafter fully described and claimed.

In the accompanying drawings forming a 55 part of this specification, and in which like characters of reference indicate corresponding parts; Figure 1 is a view in vertical lon-

itudinal section through one form of receptacle provided with the novel form of rim constituting the subject matter of the present invention. Fig. 2 is a top plan view of the 60 receptacle with the closure removed. Fig. 3 is an enlarged detail sectional view through the rim of the receptacle and that of the closure.

The receptacle 1, which is made of sheet 65 metal may be circular as shown, and is provided with a bottom 2 that is held assembled with the walls of the receptacle by being beaded thereto at 3, in the usual manner. This mode of securing the bottom to the 70 receptacle will render the employment of solder unnecessary, but it may be used.

The novelty of the present invention resides in the peculiar rim that is assembled with the mouth portion of the receptacle, 75 and is designed by coaction with the closure to secure an absolutely air tight joint between the parts. As shown more clearly in Fig. 3, the mouth portion of the receptacle is 80 overturned to form a bead 4, which is approximately U-shaped in cross section although it may be of other contours, and which is arranged on the exterior of the body.

Disposed upon the upper edge of the receptacle is the rim referred to, which is provided with a double rebent bead 5 that encloses the bead 4, and the inner edge 6 of which lies contiguous to or impinges against the bend of the bead 4. That portion of the rim that is disposed within the receptacle 90 from the bead 4 downward some distance bears closely against the inner wall of the former and is then formed into a curled seal or closure engaging member 7, which, under pressure, will yield sufficiently to permit the 95 positioning of the closure, and upon the removal of the latter will expand to its original proportions. The yielding of the inner curl 100 a of the seal 7 is effected by disposing the side of the curl against the adjacent wall of the outer curl b of the seal, instead of its edge c, as has heretofore been the practice, so that under pressure from the closure, the curl a will slide against the wall of the curl b and thus permit proper seating of the closure. 105 This compression of the seal is still further assisted by projecting the edge c inward beyond the horizontal axis of the seal, as clearly shown in Fig. 3. The cupped portion 8 of the closure 9 bears against the inner wall 110 or periphery of the seal 7, and as will be obvious only a very small part of the seal

contacts with the closure, so that a perfectly air and liquid tight seal or joint may be secured.

The seal is assembled with the receptacle by the employment of suitable beading rolls, and the union between the parts of the seal and of the receptacle is of such intimate character that the employment of solder is rendered unnecessary, although as an additional precaution solder may be employed between the lower edge of the rebent bead 5 and the body of the receptacle.

As will be obvious, and understood by reference to Fig. 2, the seal or rim is seamless, and this will insure the proper coaction, without danger of breakage or splitting between the cupped portion of the closure and the seal.

An important feature of the invention resides in the disposition of the seal relative to the upper edge of the rim, it being seen by reference to Fig. 3 that the upper edge of the former occupies a plane coincident with that of the rim, or in other words is flush therewith. The seal is relatively small in diameter, and therefore constitutes a pouring edge that will facilitate the discharge of the contents of the can, and prevent the retention of any measurable quantity thereof.

The walls of the cupped portion of the closure 9 are disposed approximately at right angles to the plane of the bottom thereof, and this will insure the most stable union between the closure and the seal. As usual, the closure is provided with an outstanding

flange 10 formed at its periphery with a bead 11 to bear upon the crest of the rebent bead 5.

The improvements herein defined are simple in character, but will be found thoroughly efficient for the purpose designed and will coact in the production of a durable, practical and thoroughly reliable form of sheet metal receptacle for containing paints, oils, food products or in fact any substance that it is desired to shield against the deteriorating effects of the atmosphere.

What is claimed is:

1. A receptacle having a seamless rim formed into a curled seal, the inner curl of which is arranged to slide against the adjacent wall of the outer curl when the seal is subjected to pressure.

2. A receptacle having a seamless rim formed into a curled seal, the edge of the inner curl of which projects beyond the horizontal axis of the seal.

3. A receptacle having an inward projecting seamless rim formed into a curled seal, the opposed portions of which are arranged for sliding movement relatively to each other under pressure.

In testimony that I claim the foregoing as my own, I have hereto affixed my signature in the presence of two witnesses.

CHARLES E. BERTELS.
